UNITED STATES PATENT OFFICE.

AUGUST HEINE, OF SILVER CREEK, NEW YORK.

SEPARATING-MACHINE.

SPECIFICATION forming part of Letters Patent No. 465,574, dated December 22, 1891.

Application filed April 3, 1891. Serial No. 387,524. (No model.)

To all whom it may concern:

Be it known that I, AUGUST HEINE, a citizen of the United States, residing at Silver Creek, in the county of Chautauqua and State 5 of New York, have invented new and useful Improvements in Separating - Machines, of which the following is a specification.

This invention relates to a separating-machine suitable for purifying middlings and 10 other substances, and which comprises an inclosing case and an air-circulating device arranged within the case, whereby the body of air contained in the case is kept in circulation without drawing in air from the outside 15 or discharging air from the case, so that the material which is fed into the case is separated into different grades by an air-current which takes up the light material and after 20 depositing the same is again brought in contact with fresh material to be separated.

The object of this invention is to increase 25 the efficiency of this class of machines by lengthening the time during which the material is subjected to the separating action of the air-current, and to provide means for nicely regulating the action of the air-current.

In the accompanying drawings, Figure 1 is a sectional elevation of my improved machine. Fig. 2 is a cross-section in line $x-x$, Fig. 1. Fig. 30 3 is a horizontal section in line $y-y$, Fig. 1. Fig. 4 is a vertical section of a portion of the air-circulating device on an enlarged scale.

Like letters of reference refer to like parts in the several figures.

35 A represents the case of the machine, which consists, essentially, of side walls a , front wall a' , rear wall a^2 , and a closed top a^3 .

B represents the feed-hopper, arranged in the upper front portion of the case, and provided 40 in its discharge-opening with a feed-roller b .

D D' D² represent a series of inclined shelves arranged underneath the feed-hopper and upon which the middlings or other material to be separated are delivered by the hopper. These shelves incline downwardly with their rear ends, and their elevated front ends are arranged at some distance from the front wall a' .

50 E represents an elongated fan or air-circulator, whereby the body of air contained in the case is caused to circulate in the same

without admitting or discharging air. This fan consists, essentially, of an endless belt or apron F, arranged vertically in rear of the inclined shelves and provided with a series of transverse blades f. The upper portion of the belt passes around a roller G, arranged transversely in the upper portion of the case and provided with annular flanges g g, which hold the belt against lateral displacement.

H represents a roller supporting the lower portion of the belt and made somewhat smaller in diameter than the upper roller. The lower roller is preferably arranged with its front side underneath the front side of the upper roller, so that the front portion of the belt travels upwardly in a vertical line, while the rear or returning portion inclines from the upper roller forwardly to the lower roller. The blades of the fan are composed of slats or strips secured to the outer side of the belt in any suitable manner.

I represents curtains or flaps, whereby the middlings and dust are prevented from collecting on the fan-blades and belt. Each of these curtains extends across the entire space between two fan-blades, and is secured with its front or advancing edge to the base of one blade, while its rear or retreating end is secured to the outer edge of the next succeeding blade, thereby forming a flexible incline from the base of each blade to the top of the succeeding blade. The length of the curtains from blade to blade is such that when the fan-blades pass from one roller to the other on the straight portion of the belt the curtains are loose and wrinkled; but when the blades pass around the periphery of the rollers, where the outer edges of the blades diverge radially, the curtains are drawn taut.

Dust or other material collecting upon the loose curtains during the upward passage thereof is dislodged by the sudden stretching or tightening of the curtains as they pass around the upper roller. The ends of the belt are preferably secured together by placing them between two adjoining blades and clamping these two blades together by means of bolts i, as represented in Figs. 1 and 4. The depressed rear edges of the shelves D D' D² are arranged at a short distance from the front side of the fan, so as to form a passage through which the air can move upwardly and the material can pass

85 90 95 100

downwardly. The belt carries the adjacent portion of the air with it in the direction in which it moves, and so causes an ascending current to travel in a straight line upwardly 5 between the front portion of the belt and the inclined shelves. The distance through which this current moves upwardly and the time during which the descending material is exposed to the action of the air-current depends 10 upon the length of the belt, and can be extended as far as necessary to effect the desired separation while keeping the size of the separating-rollers as small as is consistent with the easy movement of the belt. The effective upright 15 portions of the fan are thereby proportionately lengthened, and the ineffective curved top and bottom portions are correspondingly shortened, thereby rendering this fan much more efficient than a circular fan. While the 20 middlings or other material to be separated are falling from the top shelf D through the space between the shelves and the front portion of the belt they encounter the upward current of air, which causes the light particles 25 to be separated from the heavier particles. The heaviest particles drop through the air-current and escape through the discharge-spout J. The lighter particles are driven by the ascending air-current through the spaces 30 between the lower shelves D² and over the front edges thereof into a discharge-passage J', formed between the front wall a' and the front ends of the shelves. The still lighter particles are driven by the air-current 35 through the space between the top shelf D and the next lower shelf D' and are discharged through a spout J², while the lightest particles are driven over the top of the fan into the rear portion of the inclosing case. 40 I represents partitions arranged vertically between the shelves and partly closing the passages between the same, thereby preventing too heavy currents of air from passing between the shelves. The lower shelves D² 45 are arranged in guides, so as to be capable of adjustment toward and from the fan. When the rear ends of the shelves are adjusted closely to the fan, the blast of air delivered by the latter is more effective and lifts a heavier grade of material, while the air-current is 50 weaker when the shelves are arranged at a greater distance from the fan, and consequently less able to lift heavy material. 55 l represents a vent formed in the wall separating the spout J from the spout J', and through which any fine dust which rises in the spout J may escape into the spout J'. The roller supporting the upper portion of the fan-belt is arranged at some distance 60 low the top of the case, so as to leave a space between the top of the case and the upper portion of the fan-belt passing around the upper supporting-roller. The lightest impurities and fine dust raised above the uppermost 65 shelf by the upward current are carried over the top of the fan and into a settling-chamber

M, formed between the rear side of the fan and the rear wall of the case.

N represents a valve whereby the grade of material carried by the fan into this settling-chamber is regulated. This valve is arranged transversely across the space in the upper portion of the case above the front portion of the upper roller and is pivoted in the side walls so that it can be tilted. When the lower 70 edge of the valve is arranged closely to the fan-blades, the light particles are compelled to pass over the upper edge of the valve before they can enter the settling-chamber. Upon tilting the valve so that its lower edge recedes from the fan and its upper edge descends, as indicated in dotted lines, the light particles are not compelled to rise so high in order to enter the settling-chamber, and a coarser 75 grade of material is permitted to pass into the 80 settling-chamber.

O represents a spout arranged at the lower end of the settling-chamber for discharging the dust collected in the latter.

P represents guard plates or shields arranged along the rear side of the fan, whereby the descending air-current is closely confined to the belt and prevented from agitating the air and dust in the settling-chamber. These plates are arranged closely to the rear 90 portion of the fan and extend from the upper portion of the latter to the discharge-spout of the settling-chamber. Each guard-plate extends entirely across the settling-chamber, and its lower end overhangs the upper end of the plate next below, so as to leave a transverse space or slot p between the adjacent ends of the plates. The fine dust or other light impurities which may adhere to the returning portion of the fan-belt are thrown 95 by centrifugal force against these plates and escape through the slots p into the settling-chamber. The lower portion of the case between the discharge-spout for the purified 100 middlings and the discharge-spout for the dust in the settling-chamber is closed by a bottom q, arranged closely to the lower portion of the fan and concentric therewith.

R represents a driving-pulley secured to one end of the shaft of the upper supporting-roller, and r is a smaller pulley secured to the opposite end of said shaft for driving the feed-roller by a cross-belt S.

I claim as my invention—

1. The combination, with an inclosing case 120 provided with an inlet for the material to be separated and with outlets for the separated materials, of an upright traveling belt or apron arranged with its ascending side below said inlet and having its ascending side separated 125 from the inclosing case by an air-space, through which the air is caused to move upwardly in a straight current by said belt or apron and through which the material to be separated descends, substantially as set forth. 130

2. The combination, with the inclosing case and the endless traveling belt or apron pro-

- vided with wings on its face, of oblique flexible curtains secured with their outer ends to said wings and with their inner ends to the belt or apron, substantially as set forth.
- 5 3. The combination, with the inclosing case and a vertical air-circulator arranged within the same, of a feeder arranged above the ascending side of the air-circulator, a discharge for the heavy material, arranged at the foot
10 of the ascending side of the air-circulator, a discharge for lighter material, arranged opposite the ascending side of the air-circulator, and a discharge for the lightest material, arranged on the descending side of the air-circulator, substantially as set forth.
- 15 4. The combination, with the inclosing case and a vertical air-circulator arranged within the same, of a feeder arranged above the ascending side of the air-circulator, and a series
20 of discharge-passages for the material elevated by the air-current, arranged one above the other opposite the ascending side of the air-circulator, substantially as set forth.
5. The combination, with the inclosing case
25 and an endless air-circulator arranged within the same, of inclined shelves facing the ascending side of the air-circulator and separated by spaces which communicate at their outer ends with a discharge for the material
30 which is driven through these spaces by the

ascending air-current, substantially as set forth.

6. The combination, with the inclosing case and an endless air-circulator arranged within the same, of inclined shelves facing the as- 35 cending side of the air-circulator and made adjustable toward and from the same, substantially as set forth.

7. The combination, with the inclosing case and an endless air-circulator arranged within 40 the same, of guard plates or shields arranged along the descending side of the air-circulator, substantially as set forth.

8. The combination, with the inclosing case and the endless traveling belt or apron ar- 45 ranged vertically within the same, of an inlet for the material to be separated, inclined shelves facing the ascending side of the belt, an outlet for the heavy material below said shelves, an outlet for lighter material commu- 50 nicating with the spaces between the shelves, and a settling-chamber for the lightest material, arranged opposite the descending side of the belt, substantially as set forth.

Witness my hand this 1st day of April, 1891.

AUGUST HEINE.
